UNITED STATES PATENT OFFICE.

RICHARD W. RIGLER, OF PHILADELPHIA, PENNSYLVANIA, ASSIGNOR TO GUY H. ELMORE, OF PHILADELPHIA, PENNSYLVANIA.

JIG PLUNGER.

Application filed September 29, 1920. Serial No. 413,429.

To all whom it may concern:

Be it known that I, RICHARD W. RIGLER, a citizen of the United States, residing at Philadelphia in the county of Philadelphia, 5 and State of Pennsylvania, have invented certain new and useful Improvements in Jig Plungers, of which the following is a specification.

This invention relates to improved means 10 for driving and guiding the plungers of ore jigs and the like.

The invention resides in certain improvements in jig plungers of the type described and claimed in Patent No. 1,108,558, granted 15 August 25, 1914, to Elmore and Croll. In the structure of that patent the plunger is guided in part by guides carried by the plunger drive shaft; and the eccentric, eccentric rod and guides are housed in an oil 20 retaining casing. While the prior structure above mentioned was a marked improvement over devices which preceded it, practical experience has demonstrated the desirability of having the eccentric always accessible for inspection and repair; and the desirability of guiding the plunger independently 25 of the drive mechanism, and by means wholly beneath the drive shaft. The latter feature is particularly difficult to arrive at 30 because of the large area of the plunger, the low head room usually available, the low ratio between length of connecting rod and length of stroke, and the difficulty in maintaining the alignment of guides in the 35 wooden tanks customarily used. This difficulty is increased where the plunger has a peripheral valve of the type disclosed in my prior Patent No. 938,307, issued October 26, 1909, because the proper action of such 40 valve is independent on a reasonably accurate guiding of the plunger.

The structure of the present invention attains the desirable results above explained and provides a device which operates satisfactorily with a minimum of attention. The guides are below and wholly independent of the drive shaft, are capable of ready adjustment and are rigid when adjusted. The wrist pin is thoroughly lubricated and is protected from water and grit. The eccentric and strap, are accessible at all 50 times.

A practical embodiment of the invention

is illustrated in the accompanying drawings, in which:—

Fig. 1 is a vertical section, transverse to the drive shaft, on the line 1—1 of Fig. 2

Fig. 2 is a vertical section, the plane of section passing through the axis of the drive shaft and wrist-pin.

Fig. 3 is a horizontal section on the line 3—3 of Fig. 1.

Fig. 4 is an enlarged fragmentary section of the eccentric and its hub, showing the taper pin used to lock the eccentric in 65 its adjusted positions.

Fig. 5 is an enlarged fragmentary section of a portion of the plunger, and of the guide and guide-way.

Fig. 6 is a section on the line 6—6 of 70 Fig. 5.

Fig. 7 is a perspective view of the guide-way.

Fig. 8 is a perspective view of the guide.

Fig. 9 is a perspective view of a portion 75 of the plunger flange, showing the seat in which the guide is adjustably mounted.

The wooden walls of the plunger-chamber of an ordinary jig-tank are shown at 11. To protect against wear these have a metal 80 lining 12, held by bind-strips 13. A plunger 14 of laminated wood construction works in this chamber, but is materially smaller than the inside dimensions of the chamber, to allow water to pass around the edges of 85 the plunger as the latter moves upward, a flap-valve 15 prevents reflux of this water when the plunger moves downward, so that the downward movement of the plunger forces water through the jig screen (not 90 shown), in the usual manner.

The flap-valve 15 extends around all four sides of the plunger, and is supported and limited in its movements by an oblique flange 16, which extends downward and outward 95 from a rectangular yoke 17 bolted to the top of the plunger 14. The yoke 17 can be cast in one piece, and is formed with four seats 18, each having a rear flange 19, and a side flange 20.

On each of the four seats 18 is mounted a corresponding guide 21, the guides being opposed to each other in pairs, as is best shown in Fig. 3. Each guide 21 works in a corresponding channel guide-way 22 bolted 105 to the walls 11 of the plunger-chamber, and

extending from about the upper limit of movement of the plunger 14 to a point near the top of the tank. The form of these guide-ways is best shown in Fig. 7, and 5 their length is sufficient to ensure accurate guiding of the plunger under all conditions.

Each guide 21 is adjustable toward and from the companion guide of its pair, the clamping bolts 23 passing through elongated slots 24 to permit the necessary movement. Each guide-way 22 is adjustable laterally, as the bolts 25 which hold them in place pass through slots 26. These adjustments are desirable to correct for irregularities in the dimensions of the tanks, and 15 ensure accurate guiding.

To assist in making and maintaining the adjustment of the guides 21 each is backed up by a thrust screw 27 passing through flange 20 19 and locked by a check nut 28, and the upper ends of the opposed guides of each pair are tied together by rods 29 having adjusting-nuts 30. To secure and maintain parallelism of adjacent guides 21, they are connected 25 in pairs by tie rods 31 having adjusting nuts 32.

The construction above described permits the parts to be accurately alined and adjusted, and ensures the maintenance of such 30 adjustment.

Mounted in bearings 33, and extending across the top of the plunger-chamber is the plunger drive-shaft 34. This may be driven by a pulley 35, or by any other suitable 35 means, and carries an eccentric for reciprocating the plunger 14. This eccentric is made up of two relatively adjustable parts, an eccentric circular hub 36, and an eccentrically bored rim 37, which may be swiveled on the hub to vary the throw of the eccentric. The rim 37 and the hub 36 may be locked together in various adjusted relations by a taper pin 38, passed through a tapered hole offered by the registry of any two of 40 two series of spaced complementary notches 45 formed in the contacting edges of the hub and rim. The pin 38 is held in place by a castellated nut 39, and cotter pin 40.

The rim 37 has peripheral flanges 41 to 50 retain the divided eccentric strap 42. The parts of this strap are held together by studs and nuts indicated at 43, and the eccentric is lubricated by a grease-cup 44. The eccentric rod 45 is integral with the lower 55 half of the strap, and has a bushed wrist-pin bearing 46 at its lower end.

The wrist-pin bracket 47 is bolted to the upper face of the plunger 14, and is of special form designed to maintain a bath of oil 60 around the wrist-pin. It includes a deep cup 48, open at its top, and completely protected against the entrance of splashing

water by a surrounding pendant skirt 49 formed on the rod 45.

The wrist-pin 50 is inserted in a hole bored 65 through the base of the cup 48. The pin is retained, and leakage of oil from the cup is prevented by the tapered threaded plugs 51. Oil may be added to the cup 48 through the 70 filling pipe 52.

The invention provides for the proper lubrication and protection of the wrist-pin, and the proper guiding of the plunger. It permits the adjustment of the guides and guideways when necessary. The use of relatively long guides and guideways, which extend well above the wrist-pin, precludes any cramping of the plunger due to the lateral thrust of the eccentric rod, and ensures the proper functioning of the flap valve on all 75 sides of the plunger and at all times. All bearings are always accessible for inspection and repair without the necessity of elaborate dismounting operations. This is particularly important in the case of the wrist- 80 pin bearing.

Since an eccentric is merely a specific type of crank in which the radius of the crank pin bearing is greater than the radius of the crank, I use the term crank as a generic 90 term to include eccentrics and other cranks. Various types of cranks are used in this art, but the eccentric has advantages arising from the large bearing surface and the readiness with which the throw may be changed 95 as described above.

What is claimed is:—

1. The combination of a jig plunger; a driving shaft mounted above said plunger; a crank carried by said shaft; a connecting rod connected to said crank; a wrist pin connecting said connecting rod and said plunger; a cup mounted on said plunger and serving to retain a bath of oil around said wrist pin; a skirt mounted on said connecting rod and housing the upper margin of said cup; and means for guiding said plunger. 100

2. The combination of a jig plunger; a driving shaft mounted above said plunger; a crank carried by said shaft; a connecting rod connected to said crank; a wrist pin connecting said connecting rod and said plunger; a cup mounted on said plunger and serving to retain a bath of oil around said wrist pin; a skirt mounted on said connecting rod and housing the upper margin of said cup; guides for said plunger mounted below said driving shaft; and coating guides on said plunger extending above and below said 105 wrist pin. 110

In testimony whereof I have signed my name to this specification.

RICHARD W. RIGLER.
